LOCOMOTIVE STARTING VALVE

Bengt E. Folke, Lafayette, Ind., assignor to
 Franklin Railway Supply Company, New York,
 N. Y., a corporation of Delaware

Application September 22, 1928, Serial No. 307,625

7 Claims. (Cl. 121—142)

My invention relates to locomotives and particularly to novel means for manually changing the valve cut-off.

It has long been known and more recently demonstrated in practice that maximum efficiency and fuel economy is obtained in locomotives having a limited maximum cut-off, for example, a cut-off of 55—65%. However, while this highly desirable result is accomplished it entails somewhat serious objections, in that it impairs the starting effort, particularly in some positions of the cranks.

Efforts have been made to provide means to supplement the tractive effort at starting and slow speeds by increasing the period of full steam pressure, but all such means known to me have certain objections, that tend to off-set the advantages.

An object of my invention is to provide a supplemental or auxiliary valve adapted to admit the steam at boiler pressure to the cylinder throughout 90% of the stroke, said valve being manually thrown into and out of operation and reciprocated by the same gear that moves the main valve.

By properly designing the steam passages through the valve and correlating the size of the passages to the available steam pressure, I am able to automatically proportion the steam admission to the speed of the locomotive. In other words, I am able to provide for 90% cut-off with full pressure at very slow speeds with a gradually reduced pressure available throughout 90% of the stroke as the speed increases. This is accomplished by providing a relatively small intake pipe. This has another important advantage, in that it is instantly effective under slipping conditions. If the drivers begin to slip, the auxiliary power applied thereto is instantly reduced without action by the engineer. This for the reason that with rapidly turning wheels the amount of steam that can be admitted through the relatively small ports provided for auxiliary admission is insufficient to provide any appreciable amount of power. In other words, under these conditions the long cut-off is practically ineffective.

My invention will be more readily understood by reference to the drawings, in which

Fig. 1 is an elevation partly in section showing a portion of a locomotive to which my improvement has been applied.

Fig. 2 is a sectional view on the line 2—2 of Fig. 1.

Fig. 3 is an enlarged sectional view through the starting valve and controlling mechanism therefor.

Fig. 4 is an end view of the construction shown in Fig. 3.

Fig. 5 is a sectional view on the line 5—5 of Fig. 3.

Fig. 6 is a plan view of the bell crank for throwing the valve into and out of operation, and

Fig. 7 is a plan view of the yoke connecting the valve stem or piston rod to the operating rocker.

In the drawings, the locomotive valve gear is indicated generally at A, the steam cylinder at B, the main valve at C, and my novel starting valve at D. The valve gear may be of any preferred form, the well-known Walshaert gear being illustrated.

My auxiliary valve, as best shown in Fig. 3, comprises a casing or cylinder 10, having an inlet 11 and outlets indicated in dotted lines at 14—15. The casing is preferably mounted on the top of the steam chest by means of the heavy bracket 10a. As shown in Fig. 1, pipes 14—15 extend from the respective outlets and communicate with openings in the steam chest containing the main valve C. These openings are called peep-holes. Thus, steam is admitted direct from the steam pipe or boiler through the inlet 11, and after passing through the starting valve, directly into the steam cylinder.

The casing 10 is provided with the usual bushing 17 and with a reciprocating balanced valve 18 having a stem or piston rod 19 which projects through a packing gland 20 in an end wall of the cylinder. In the position of the valve shown in Fig. 3, steam is permitted to pass directly from the inlet, through the ports and out through the pipe 14 into the left hand end of the cylinder shown in Fig. 1 regardless of the position of the main valve. This is illustrated in Fig. 2.

Connected to the projecting end of the valve stem 19 is a yoke 21 best shown in Fig. 7, in the two arms of which are mounted stud-bolts 22. These bolts engage in ear pieces 23 having flanges 24 that are bolted through each other and through the wall of a rocker 25. The ears 23 are so positioned as to leave a space 26 between the inside faces of the ears and the outside faces of the rocker. The rocker is adapted to be oscillated by means of a link 27 that is connected to a portion of the valve gear immediately adjacent to the connection to the main valve.

Whether or not the starting or auxiliary valve

is reciprocated under the action of the valve gear is dependent on the position of the fulcrum block 28 that is slidably mounted within the recess or way 29 in the rocker 25. This fulcrum or slide block is held between the double arms 30 of a bellcrank that is pivoted at 31 to a portion of the cylinder end wall, the two arms 30 straddling the rocker and being designed to be moved into and to occupy the space 26 between the ears 23. The 10 other arm 32 of the bell crank is offset and projects downwardly to be engaged by a plunger rod 33 that projects into a cylinder 34 and has a piston 35 secured thereto. A stiff spring 36 bears at one end against the piston and at its opposite end against a cap 37 that closes the otherwise 15 open end of the cylinder. Air is admitted through the pipe 38 into the space within the cylinder and is adapted to move the piston into the position shown in Fig. 3 thus oscillating the bell crank and moving the fulcrum block into the position shown 20 in that figure. The pipe 38 extends from the air cylinder to a valve 39 having a foot operated pedal 40 located in the cab of the locomotive and adapted to be actuated manually by the engineer.

25 The operation is as follows: When the engine is to be started or when its speed has been reduced to a point where a longer cut-off is required, the engineer steps on the pedal 40 thus admitting air into the cylinder 34 and moving the piston and connected parts into the position shown in Fig. 3. In this position, motion will be transmitted from the valve gear to the valve 18, thus opening and closing the ports, and due to the design and arrangement, admitting steam at substantially 30 boiler pressure to the main cylinder throughout 35 90% of the stroke without regard to the operation of the main valve.

40 As the speed of the engine increases, the full boiler pressure will not be available throughout the entire 90% of the stroke due to the fact that the pipe connections from the auxiliary or starting valve to the cylinder are made sufficiently small to prevent the passage of the required volume of steam at boiler pressure. In the design 45 here submitted, the outlet pipes are $1\frac{1}{4}$ inches which has been found to be a satisfactory size in order to accomplish the desired purposes. As the speed of the engine still further increases, the effect of the starting valve is further lessened until at a speed of 15 to 18 miles per hour, the effect 50 is not appreciable over a normal 65% cut-off arrangement. The engineer will then release the air valve allowing the return of the piston to its rearward position. This will effect movement of the plunger and the return of the fulcrum block 55 to a position at which the pivot through the fulcrum block is coincident with the pivot of the rocker 21. At this point it will be seen there will be no further reciprocation of the valve 60 18 and it will be held in a middle position with both ports closed. Thus during normal operation of the engine the starting valve is wholly inoperative and does not affect in any way the operation of the main valve with its designed cut-off.

65 The size of the outlets which have been described herein as $1\frac{1}{4}$ inches will vary somewhat according to boiler pressures, but they should be so designed as to limit the volume of steam that 70 may be passed therethrough to an amount appreciably less than is passed through the main valve at maximum cut-off.

75 Another advantage in the use of small pipe connections is that the clearance space is not greatly increased. As all the steam in the clearance

space is exhausted and lost at each cycle, this space should be kept as small as possible.

I claim:—

1. The combination with a steam cylinder, steam chest having peep holes, and valve gear of a locomotive, of a starting valve having an inlet and outlets mounted adjacent to said steam chest, a pipe connection from a steam pipe to the inlet of said starting valve, pipes extending from the outlets of said starting valve to the peep holes of the steam chest, crank mechanism connecting the starting valve to the valve gear, and means for shifting said crank mechanism to render said starting valve operative or inoperative by said valve gear. 80

2. In a steam locomotive having a cylinder, a piston, a steam chest, main steam supply ports and passages, a main steam valve set to give a limited cut-off when in "full-gear" position, and an adjustable valve gear for operating and reversing said main valve and altering its cut-off within the limited range for which the valve is set; the combination with said adjustable valve gear, of means providing by-passes for delivering supplementary steam around said main valve to the cylinder independently of the main valve in order to start the locomotive, supplementary valve means independent of the main valve adapted to open and close said by-passes, operating means connected between said adjustable valve gear and said supplementary valve means, and means for shifting said operating means, so as to render the supplementary supply means operative or inoperative as required but without affecting the cut-off of the main valve. 90

3. The combination with a cylinder, main valve and valve gear of a locomotive, said valve gear including a combination lever, of means providing by-passes for steam around said main valve to the cylinder, starting valve means adapted to open and close said by-passes, operating means between the combination lever and said starting valve means, and means for shifting said operating means so as to render the starting valve means operative or inoperative as required. 100

4. In a steam locomotive having a cylinder, a piston, a steam chest, main steam supply ports and passages, a main steam valve set to give a limited cut-off when in full gear position and an adjustable valve gear for operating and reversing said main valve and altering its cut-off within the limited range for which the valve is set; the combination with said adjustable valve gear, of means providing by-passes for delivering supplementary steam around said main valve to the cylinder independently of said main valve in order to start the locomotive, supplementary valve means independent of the main valve adapted to open and close said by-passes, operating means connected between said adjustable valve gear and said supplementary valve means, said operating means including a rocker link and a block slidably therein, and means for shifting said block either to a position where the operating means will be operative or to a position where it will be inoperative whereby to render said supplementary valve means operative or inoperative as required but without affecting the cut-off of the main valve. 110

5. Means for starting a limited cut-off locomotive having a cylinder, a piston, a steam chest, main steam supply ports and passages, a main steam valve, and an adjustable valve gear for operating and reversing said main valve and altering its cut-off, said main valve and said 120

- adjustable valve gear being set so as to give a limited cut-off when in "full-gear" position; said means including in combination with said adjustable valve gear, supplementary passages for supplying steam to the cylinder independently of the main valve, starting valve means independent of the main valve for controlling said supplementary passages, means cooperating with the adjustable valve gear for opening and closing 5 sages, operating means connected between said valve gear and said starting valve means, said operating means including a member which is movable either to a position where the starting valve means will be operative or to a position where the starting valve means will be inoperative, and means for moving said member to one or the other of said positions as desired without affecting the cut-off of the main valve. 80
- 10 said starting valve means in timed relation to the piston movement to admit steam to the cylinder throughout sufficient of the piston stroke to effect starting of the locomotive, said means for opening and closing the starting valve means including 15 a member which is movable either to an operative or to an inoperative position, and means for moving said member to render said starting valve means operative or inoperative as desired without affecting the cut-off of the main valve. 90
- 20 6. Means for starting a limited cut-off locomotive having a cylinder, a piston, a steam chest, main steam supply ports and passages, a main steam valve and an adjustable valve gear for operating and reversing said main steam valve and altering its cut-off, said main valve and said valve gear being set so as to give a limited cut-off when in "full-gear" position; said means including in combination with said adjustable valve gear, supplementary passages for supplying steam 25 to the cylinder independently of the main valve, starting valve means independent of the main valve for controlling said supplementary pas- 30 sages, operating means connected between said valve gear and said starting valve means, said operating means including a member which is movable either to a position where the starting valve means will be operative or to a position where the starting valve means will be inoperative, and means for moving said member to one or the other of said positions as desired without affecting the cut-off of the main valve. 95
7. In a steam locomotive having a cylinder, a piston, a steam chest, main steam supply ports and passages, a main steam valve set to give a limited cut-off when in "full-gear" position, and an adjustable valve gear for operating and reversing said main valve and altering its cut-off within the limited range for which the valve is set; said valve gear including a combination lever; the combination with said adjustable valve gear and its combination lever, of means providing by-passes for delivering supplementary steam around said main valve to the cylinder independently of said main valve in order to start the locomotive, supplementary valve means independent of the main valve adapted to open and close said by-passes, operating means connected between said combination lever and said supplementary valve means, and means for shifting said operating means so as to render the supplementary supply means operative or inoperative as required without affecting the cut-off of the main valve. 100
